AUGER DRILL

Earl M. Spry, Plymouth, Pa.

Application December 30, 1947, Serial No. 794,517

5 Claims. (Cl. 255—69)

1

The present invention relates to boring tools and more particularly to an improved drill or auger stem or body for use in drilling coal, rock, shale, gypsum, iron ore, and like material.

In drill stems or bodies of the type to which this invention relates the transverse section thereof is of vital importance since its shape is the material factor in obtaining efficient results, and such stems, as heretofore constructed, are lacking in such section shape as will pull the cuttings out with a minimum of accompanying dust; are formed with improper flight angles; have rough or sharp edges susceptible of injuring the hands of the operator; and have been designed with little regard to whip incident to drilling operations.

Some of the objects of the present invention are: to provide an improved drill stem or body formed as quarter octagon steel with a new and novel transverse section; to provide a drill stem materially stronger than any heretofore in use and wherein equal distribution of material is obtained; to provide a drill stem having a section which gives maximum resistance to whip in use so that crystallization of the steel is eliminated and breakage reduced to a minimum; to provide a drill stem wherein there is a minimum flight drag due to the smooth surfaces of the flights; to provide a drill stem wherein a novel transverse section ensures the cuttings being pulled out with practically all dust being eliminated; and to provide other improvements as will hereinafter appear.

In the accompanying drawings, Fig. 1 represents a side elevation of a drill stem embodying the present invention, the same being shown prior to twisting; Fig. 2 represents the same in finished form after twisting; and Fig. 3 represents a section on an enlarged scale taken on line 3—3 of Fig. 1, as illustrative of the section throughout the length of the stem, but indicating in dotted lines the bore of a hole to illustrate the relation of the stem section thereto.

Referring to the drawings, Fig. 1 illustrates a bar 10 of drill steel preliminarily shaped from square bar stock by the usual rolling operation to pass the bar through a preshaped die to transform the square section into the modified quarter octagon section of the present invention. In this drill section two opposite corners of the former square section provide two smooth, plane surface edges 11 and 12 as outer faces respectively of two diametrically opposite, relative narrow ribs 13 and 14 of like length extending longitudinally throughout the length of the bar 10. The base of the rib 13 curves outwardly to merge

2

smoothly into the former sides 15 and 16 of the square section stock, which diverge to intersect respectively two smooth, plane surfaces 17 and 18 of two parallel lines of slightly rounded intersections 20 and 21. Likewise, the base of the rib 14 curves outwardly to merge smoothly into the former sides 22 and 23 of the square section stock, which diverge to intersect respectively the aforesaid surfaces 17 and 18 in two parallel lines of slightly rounded intersections 24 and 25. The two lines of intersections 20 and 21 lie in the same transverse plane, while the two lines of intersections 24 and 25 lie in a different transverse plane, the two planes being parallel and spaced by the width of the respective surfaces 17 and 18. Thus, these surfaces 17 and 18 are the result of displacing the former two opposite corners of the square section stock by truncated portions respectively, while the ribs 13 and 14 are elongated extensions of the other two corners of the former square section stock. As a result of this transition from a square section stock to a modified quarter octagon section, a relatively heavy body core is obtained with the two surfaces 17 and 18 spaced apart a shorter distance than the edges 11 and 12 upon the diametrically extended ribs 13 and 14. This is an important distinction over prior drill stem sections in that a substantially massive body or core portion is provided capable of effectively resisting whip and distortion when the stem is in use in the complete drill assembly.

With the novel section of the invention formed in the bar as above described, and as shown in Fig. 1, the body of the drill blank is then twisted about its longitudinal axis in a well-known manner, either heated or cold, according to the character of the steel from which the stem is rolled. When properly twisted, the ribs 11 and 12 form equally spaced spiral flights throughout the length of the stem, while maintaining the required novel section at all transverse points throughout the length of the stem. In consequence a stem is provided in which the rib edges 11 and 12 are equally spaced radially from the center of the core body and give a diameter arranged to fit the internal diameter of the hole being bored, while the smooth surfaces 17 and 18 are each well spaced from the wall of the hole to thereby provide appreciable equal spiral clearances which serve to convey displaced material from the hole entering end of the stem to the other end. Due to the smooth and rounded intersections and edges crushing of the material into dust form is practically eliminated. The efficiency of this non-crushing feature is largely

due to the appreciable clearances, shown in Fig. 3, opposite the respective surfaces 17 and 18, each clearance communicating at its ends with a pair of spiral passages running lengthwise of the stem. Thus, displaced material is more or less free for self-adjustment without encountering grinding surfaces.

For assembly for use in drilling operations with conventional drill bits or jackbits and power hammers or jackhammers, one end of the aforesaid stem is formed with an integral extension 26 which is externally threaded to mount a jackbit as the drill for working end of the stem. The threaded construction shown is preferred because present day removable bits are threaded but other bit-securing means can be employed since this forms no part of the present invention. The opposite end of the stem is formed with an elongated shank 27 of such lengths as will allow proper connection to the jackhammer and in section may be of hexagon section or such other section as will allow attachment of the aforesaid jackhammer. Also, at a convenient distance from the end of the shank a circumferential integral collar 28 is provided to receive the thrust of the hammer in use.

It will now be apparent that a drill steel stem of novel quarter octagon section has been devised differing from a conventional quarter octagon steel in that two opposite sides are reduced in spaced diameter and so working the material that displaced material is added to the other two opposite sides in the form of outwardly projecting ribs. By twisting this novel section of quarter octagon steel, a steel stem is formed far stronger than various types of twisted drills now in use in that the novel section shape furnishes equal distribution of material in the ribs of the stem. Also, this section reduces whip to a minimum and thus eliminates crystallization of the steel whereby less breakage occurs. This novel stem has no sharp or rough edges which heretofore have caused cutting of the hands in use. Furthermore, the elongated twist with the smooth clearances provided furnishes a minimum flight drag due to the smoothness of the flight for pulling out cuttings. This action also protects the health of the driller in that it is a dustless drill. It will be understood also that the stem is made in various lengths for starting a hole with short lengths and longer lengths as the hole becomes deeper and can be used with all types and sizes of detachable jackbits.

Having thus described my invention, I claim:

1. An auger drill formed from modified quarter octagon drill stem, comprising a solid steel body formed by two truncated sides arranged with juxtaposed spaced apart bases and outer surfaces parallel to each other and two ribs formed respectively as oppositely disposed radial extensions of said bases terminating in cutting edges, said sides and ribs extending helically substantially throughout the length of said stem in alternate radial relation, the distance between said edges being greater than the distance between said sur-

faces whereby a massive torsion resisting core is provided having a plurality of smooth helical channels between said ribs for displaced material and means respectively at the ends of said body for attaching drill bits and power hammers.

2. An auger drill formed from modified quarter octagon twisted drill stem comprising a steel body, means at one end for attaching a drill bit, means at the other end to cooperate with a power hammer, said body having a transverse section formed by two diametrically opposite ribs radially dimensioned to fit the internal diameter of the hole to be bored, and two oppositely disposed smooth surfaces respectively formed by a pair of body sides converging outwardly from said ribs a radial distance less than the spacing of the ends of said ribs, whereby a massive torsion resisting core is provided having clearances between said surfaces and the wall of said hole during a boring operation.

3. A section of a modified quarter octagon steel twisted drill stem of such uniform section throughout its operative length comprising a body, two oppositely disposed truncated sides integral with said body, and two ribs integral with said body and projecting oppositely between said truncated sides, the dimension of the spacing between the edges of said ribs being greater than the spacing between the surfaces respectively formed by the convergence of said truncated sides.

4. A drill rod comprising a body of substantially square cross section, two oppositely disposed corners of the body section being truncated to provide a pair of relatively narrow faces, the remaining corners being provided with extending ribs, the distance between the extremities of the ribs being greater than the distance between the truncated corners, said body with the ribs being twisted in helical formation whereby a massive torsion resisting core is formed with helical ribs and clearances.

5. A drill rod blank comprising a twisted body of substantially square cross section, two oppositely disposed corners of the body section being truncated, and the other two oppositely disposed corners being provided with extending ribs, the distance between the extremities of the ribs being greater than the distance between the truncated corners.
